GASOLINE STOVE

George E. Pickup, Newark, Ohio, assignor to The Wehrle Company, Newark, Ohio, a corporation of Ohio

Application March 24, 1933, Serial No. 662,407

10 Claims. (Cl. 158—81)

The invention pertains to gasoline stoves, and has particular reference to an improved generator for converting the liquid fuel into a gaseous fuel for purposes of combustion.

5 The primary object of the invention is to provide a new and improved generating means for gasoline cook stoves and the like with a view to eliminating difficulties heretofore experienced with the accumulation of carbon within the generator.

10 Gasoline stoves of the prior art have commonly employed generators in the form of a single tube communicating at one end with a source of fuel and having at its other end a needle valve 15 for controlling the discharge of the fuel in gaseous form to a manifold, said valve being operated by a rod extending through the tube for manual operation at the front of the burner box. In the use of such stoves, an unavoidable accumulation of carbon occurs within the tube, and the difficulty above referred to concerns more especially the clogging of the discharge orifice controlled by the needle valve, said orifice being of a very small diameter, in the order of a few 20 thousandths of an inch.

25 My invention more specifically stated, aims to provide an improved generator embodying two parts or sections, one of which receives the fuel from the supply tank and constitutes in effect 30 a vaporizing chamber, and the other of which receives the fuel in vaporized form and delivers it to the manifold.

35 A further object is to provide a generator having primary and secondary parts of the character above referred to, with the vaporizing member arranged for convenient removal for the purpose of removing the carbon therefrom without disturbing the needle valve mechanism in the other member.

40 A general object is to provide a burner structure having an improved generator of the character set forth, which is simple and inexpensive in construction, and reliable in operation.

45 The objects of the invention thus generally stated together with other and ancillary advantages, are obtained by the construction and arrangement illustrated in the accompanying drawings forming a part hereof in which:

50 Figure 1 is a fragmentary top plan view of a burner structure embodying my invention, the same being shown in connection with a suitable fuel supply tank.

55 Fig. 2 is a fragmentary sectional view taken approximately in the plane of line 2—2 in Fig. 1, but on an enlarged scale.

Fig. 3 is a fragmentary transverse sectional view taken approximately in the line of 3—3 of Fig. 2.

In the preferred embodiment of the invention illustrated, the burner structure comprises a 5 manifold 1 with which one or more burners are in valve controlled communication. Herein I have shown a main burner 8 formed in two segmental sections arranged in laterally spaced relation upon an arm 9 of the manifold, and an 10 auxiliary burner 10 communicating with the manifold through the medium of a tubular arm 11. Valves 12 and 12' (see Fig. 3) are operated by rods 13 and 13' extending forwardly through the front wall 14 of the burner box and provided 15 with suitable handles 15.

Also communicating with the manifold through the medium of an arm 16 is a generator burner 17 in the form of an elongated tubular member having in its upper surface a plurality 20 of grids 18. This generator burner is in constant communication with the manifold, and is initially supplied with fuel in vapor form by means of a pipe 19 receiving its supply of fuel from the upper portion of a supply tank 20 and 25 delivering such fuel to the manifold opposite the tubular arm 16 leading to the generator burner. 21 designates a secondary air mixing device embodied in the manifold at a point adjacent the discharge of the fuel vapor from the pipe 19. 30

Between the two sections of the main burner 8 and overlying the generator burner 17 is my improved generator providing a vaporizing chamber in the form of an elongated tube 22, and a discharge chamber for gaseous fuel, in the form of 35 an elongated tubular member 23. The two tubes are arranged in parallel relation but offset from each other both laterally and vertically, as shown clearly in Fig. 3, so that both tubes are disposed above the generator burner 17. Thus both tubes are arranged in a manner such as to receive heat directly from the burner 17 without increasing unduly the width of the generator burner or the space between the two sections of the burner 8. 40

At their forward ends the two tubes 22 and 23 are connected for intercommunication preferably through the medium of a fitting 24. For this purpose, the fitting 24 is constructed to provide an inclined passage 25 communicating at its lower forward end with the forward or outlet end of 50 the tube 22, and at its upper end with a horizontal passage 26 communicating with the forward or inlet end of the tube 23. Thus it will be observed, that by the construction and arrangement of the fitting 24 the vaporizing tube is disposed 55

in a plane below the discharge tube in order to collect the liquid fuel, and passage of the fuel in gaseous form to the discharge tube is retarded. The passage 26 communicating with the upper 5 end of the passage 25 is alined with the forward or inlet end of the tube 23.

Fuel is delivered to the rear or inlet end of the tube 22 by means of a pipe 27 (Fig. 1) connected by a detachable coupling 27' to the tube. 10 It is discharged in gaseous form from the rear end of the tube 23, under the control of a needle valve 28, into the forward end of a tubular arm 29 of the manifold. Air is admitted at the point of discharge in the usual manner (not shown). 15 The needle valve 28 is formed on the rear end of a rod 30 which has a screw threaded engagement with a tubular member 31 in the rear end of the tube 23, and which extends forwardly through the fitting 24 equipped with a packing 20 gland 32, the diameter of the rod being less than that of the passage 26. Operation of the rod 30 by means of a handle 33 varies the position of the needle valve 28 with respect to a discharge nozzle 34 to control the flow of fuel in a well 25 known manner.

The fuel supplied to the generator by the pipe 27 is under the control of a thermostatically actuated valve 35, which is connected by means of a pipe 36 with the supply tank 20, the latter being under air pressure delivered to the tank through the medium of a pipe 37 also in the usual manner. The valve is mounted on one end of a bracket 38 extending transversely of the generator and is actuated by a thermal element in the 35 form of a rod 39 which passes between the generator burner 17 and the generator tubes 22 and 23. The other end of the rod 39 is anchored at the end opposite the valve to an upwardly extending arm 40 on the bracket 38. The rod is 40 made of a material adapted to expand under heat, and such expansion is utilized to open the valve 35 and permit the flow of fuel to the generator through the pipe 27.

In the operation of the stove, fuel vapor is 45 supplied to the generator burner 17 by opening a valve 41 controlling the flow of fuel to the pipe 19. Upon ignition of this burner, the tubes 22 and 23 become heated and the valve 35 operated through the automatic action of the thermally 50 responsive rod 39 to permit the supply of fuel to the primary generator tube 22 by the pipe 27. This latter tube, being arranged in closely spaced 55 relation to the generator burner, becomes heated rapidly, so that the liquid fuel is converted into a gaseous fuel for passage into the upper or discharge tube 23. The latter, being also heated by the generator burner, delivers the fuel in gaseous form into the manifold for consumption by one or more of the burners 8 and 10. The generator burner 17 is maintained in operation by reason 60 of its constant communication with the manifold.

Experience has shown that the formation of carbon occurs at the point of conversion from liquid to a gaseous form, and it will be observed 65 that I have taken advantage of this fact through the provision of a primary vaporizing chamber in addition to the usual discharge chamber containing the needle valve. By this arrangement, carbon accumulating as a result of the conversion 70 of fuel from liquid to gaseous form is segregated and may from time to time be removed easily without disturbing the controlling valve device. In this latter connection, it will be observed that the primary tube 22 may be easily 75 removed by uncoupling the pipe 27 from the rear

end of the tube, and then unscrewing the tube from the fitting 24.

The thermostatic control of the fuel supply to the generator, while disclosed generally herein, forms no part of the present invention, but is disclosed more fully and claimed in my copending application Serial No. 662,406, filed March 24, 1933.

I claim as my invention:

1. In a gasoline stove, the combination with a 10 burner manifold, a main burner communicating with the manifold and having two laterally spaced sections, a generator disposed between said main burner sections and having a tube with a discharge orifice at one end opening into 15 said manifold, a needle valve controlling said orifice and having an operating rod extending through said tube, a fitting at the end of the tube opposite said orifice and having a passage therethrough for said rod of a diameter greater than said rod, said generator further comprising a vaporizing tube having one end connected with said fitting in communication with said passage and the other end connected with a source of liquid fuel, and a generator burner connected 20 with the manifold and disposed beneath said tubes in heating relation thereto.

2. In a gasoline stove, the combination of a 25 burner manifold, a generator having a tube with a discharge orifice at one end opening into said manifold, a needle valve controlling said orifice and having an operating rod extending through 30 said tube, a fitting at the end of the tube opposite said orifice and having a passage therethrough for said rod, said generator further comprising a vaporizing tube disposed in a plane below the discharge tube and having one end connected with said fitting in communication with said passage and the other end connected with a source of liquid fuel, and a burner connected 35 with the manifold and disposed in heating relation to said vaporizing tube.

3. In a gasoline stove, the combination of a 40 burner manifold, a generator having a tube with a discharge orifice at one end opening into said 45 manifold, a needle valve controlling said orifice and having an operating rod extending through said tube, a fitting at the end of the tube opposite said orifice and having a passage therethrough for said rod, said generator further comprising a vaporizing tube having one end connected with 50 said fitting in communication with said passage and the other end connected with a source of liquid fuel, and a burner connected with the manifold and disposed in heating relation to both 55 of said tubes.

4. In a gasoline stove, the combination of a 60 burner manifold, a generator having a tube with a discharge orifice at one end opening into said manifold, a needle valve controlling said orifice and having an operating rod extending through 65 said tube, a fitting at the end of the tube opposite said orifice and having a passage therethrough for said rod, said generator further comprising a vaporizing tube having one end connected with 70 said fitting in communication with said passage but at a point below said discharge tube and the other end connected with a source of liquid fuel, and a burner connected with the manifold and disposed in heating relation to both of said tubes.

5. In a gasoline stove, the combination of a 75 burner manifold, a generator having a tube with a discharge orifice at one end opening into said manifold, a needle valve controlling said orifice and having an operating rod extending through 80

said tube, a fitting at the end of the tube opposite said orifice and having a passage therethrough for said rod, said generator further comprising a vaporizing tube having one end connected with 5 said fitting in communication with said passage and the other end connected with a source of liquid fuel, and a burner connected with the manifold and disposed in heating relation to both of said tubes, said tubes being spaced apart in 10 laterally and vertically offset relation above the burner.

6. In a gasoline stove, a generator having an elongated tubular member with a discharge orifice at one end and an inlet opening at the other end, 15 a needle valve controlling said orifice and having an operating rod extending through said member with an end portion projecting beyond said inlet end, said generator further including a vaporizing chamber disposed in a plane below said tubular member and having an outlet opening connected with the inlet end of said tubular member and an inlet opening connected with a source of liquid fuel, and a burner in heating relation to 20 said vaporizing chamber and said tubular member.

7. In a gasoline stove, a fuel supply pipe, a generator having an elongated tubular member with a discharge orifice at one end and an inlet opening at the other end, a fitting having a 25 passage communicating with said inlet opening, a needle valve controlling said orifice and having an operating rod extending through said member and through said fitting, said generator further including a vaporizing tube removably connected 30 with said fitting in communication with the passage thereof, and having an inlet opening at the end opposite the fitting detachably connected with said fuel supply pipe, said tubes being disposed in spaced parallel relation, and a burner 35 in heating relation to said vaporizing tube.

8. In a gasoline stove, a fuel supply pipe, a generator having an elongated tubular member with a discharge orifice at one end and an inlet 40

opening at the other end, a fitting having a passage communicating with said inlet opening, a needle valve controlling said orifice and having an operating rod extending through said member and through said fitting, said generator further 5 having a vaporizing tube removably connected with said fitting in communication with the passage thereof, and having an inlet opening at the end opposite the fitting detachably connected with said fuel supply pipe, said tubes being disposed in spaced parallel relation, and a burner in 10 heating relation to said tubes.

9. A burner structure for gasoline stoves, comprising in combination, an elongated tubular member having a fitting at one end and a discharge orifice at its opposite end, valve means in 15 said member for controlling the discharge of fuel from said orifice and including a stem supported by said fitting, a vaporizing tube having one end detachably connected with said fitting and connected through said fitting with said tubular member, a fuel supply pipe detachably connected with the other end of said vaporizing tube, and a burner for heating said vaporizing tube.

10. A burner structure for gasoline stoves, comprising in combination, a generator including an elongated tubular member having a fitting at one end and a discharge orifice at its opposite end, valve means in said member for controlling the discharge of fuel from said orifice, a vaporizing tube having one end detachably connected with said fitting and connected through said fitting with said tubular member, a fuel supply pipe detachably connected with the other end of 20 said vaporizing tube, said tubular member and 30 vaporizing tube being arranged in spaced parallel relation but offset horizontally from each other and the connection through said fitting forming a passage inclined upwardly from the vaporizing tube and being thereby obstructed to the flow of 35 fuel in liquid form to the tubular member, and a burner beneath said member and said tube.

GEORGE E. PICKUP.
